STRAP SEAL

William C. Childress, Oak Park, Ill., assignor to
Acme Steel Company, Chicago, Ill., a corpora-
tion of Illinois

Original application February 13, 1935, Serial No.
6,309. Divided and this application May 28,
1938, Serial No. 210,753

3 Claims. (Cl. 24—23)

This invention relates to improvements in strap seals and its purpose is to provide an improved device adapted for use in uniting the overlapping ends of steel straps or other binders which are used in reenforcing boxes or packages or in binding a plurality of such boxes or packages together. The present application is a division of my original application, Serial No. 6,309, filed February 13, 1935, which describes and claims a form of strap sealing apparatus intended for use in drawing a strap taut around a box or package, cutting off the strap from the source of supply, and then uniting the overlapping ends of the strap by means of a seal which is carried into engagement with the overlapping strap ends by means of the movable head of the apparatus comprising a pair of relatively movable jaws between which a seal is adapted to be held when moved into position therein from a storage magazine, the jaws being capable of relative movement after the seal has been brought into engagement with the overlapping strap ends for the purpose of bending the seal about the strap ends and then shearing the lateral edges of the strap and seal to form an interlocking joint adapted to prevent relative endwise movement of the strap ends. The present invention is directed primarily to a seal adapted for use in the type of sealing apparatus disclosed in said application and the principal object of the present invention is to provide an improved form of seal which may be flat or substantially flat so that a large number of such seals may be stored in a limited space in a storage magazine, from which they are fed to the jaws of the sealing tool as required, during the operation of the apparatus. A further object of the invention is to provide an improved form of seal of a substantially flat or slightly curved shape which is so modified as to cause it to bend along predetermined lines when it is acted upon by the apparatus of the sealing tool so that portions of the seal are bent around the edges of the overlapping strap ends preliminary to the formation of an interlocking joint by effecting the deformation of the seal and the overlapping strap ends enclosed therein. Still another object of the invention is to provide an improved strap seal of a substantially flat or slightly curved form which is so constructed that a plurality of such seals may be stored in a limited space in a magazine and which are provided with projections so that superimposed seals are spaced slightly apart to permit their convenient engagement by the feeding device of the sealing apparatus, while at the same time materially reducing the frictional

resistance which must be overcome in moving one seal with respect to the next adjacent seal in the magazine as a seal is fed to position between the jaws of the sealing apparatus. Other objects relate to various features of construction and arrangement which will appear more fully hereinafter. 5

The nature of the invention will be understood from the following specification taken with the accompanying drawings in which certain embodiments of the improved seal are illustrated in connection with a portion of a form of sealing apparatus with which the seal may be employed. 10

In the drawings—

Figure 1 shows a perspective view of one form 15 of flat seal constructed according to the present invention, looking toward the bottom thereof, this seal being adapted to be employed with the sealing apparatus disclosed in said original application and partially illustrated in Figs. 4 to 8, 20 inclusive;

Fig. 2 is a perspective view of the completed joint which is formed by the operation of the sealing apparatus upon the form of substantially 25 flat seal illustrated in Fig. 1;

Fig. 3 is a perspective view of another form of substantially flat seal embodying the present invention, which may be employed with the sealing apparatus shown in Figs. 4 to 8, inclusive; 30

Fig. 4 shows a vertical section through a portion of the sealing apparatus of the original application referred to above, illustrating the seal of Fig. 1 positioned between the jaws of the sealing head when the head has been lowered to a position where the seal rests upon the overlapping 35 strap ends;

Fig. 5 shows an enlarged detail section taken on the line 5—5 of Fig. 4 illustrating the operation of a plunger in feeding the lowermost seal from the magazine to a position between the jaws 40 which are shown in Fig. 4;

Fig. 6 is a detail section taken on the line 6—6 of Fig. 5 showing the operation of the feeding plunger in engaging the lowermost seal of the stack when the seal is fed to the jaws of the sealing head; 45

Fig. 7 shows an enlarged detail section through the lower portions of the sealing jaws illustrating the relative positions of the bending dies, carried by the jaws, when they have bent the lateral 50 edges of the seal about the strap ends; and

Fig. 8 shows an enlarged vertical section taken through the sealing jaws at a point displaced laterally from the section illustrated in Fig. 8, 55 illustrating the relative positions of the parts

when the shearing dies have been actuated to shear the lateral edges of the strap and seal, and to deflect intervening portions thereof to provide an interlocking joint.

5 In Fig. 1 of the drawings, there is shown a form of seal 29 which has a flat central portion 29^a separated from parallel side portions 29^b by intervening longitudinal score lines or grooves 29^c which indent the metal for some distance 10 inwardly from each end of the seal so that the seal has a tendency to bend along these lines when pressure is applied to the lateral edges 29^d of the seal. These score lines 29^c may be 15 formed by compressing and indenting the metal of the seal with a resulting formation of longitudinally extending ribs on the upper side of the seal. The score lines 29^c at each end of the plate are in alignment with the corresponding score lines at the other end of the plate. At the same 20 time that the blank is punched to form the score lines, the blank may be punched to form projections 29^e which are adapted to space adjacent seal plates apart when they are stacked upon each other to form a package adapted to be 25 placed in the magazine of a sealing tool. There are preferably two such projections 29^e on each side portion 29^b of each seal and these projections are spaced inwardly from the ends of the seal. The projections opposite the score lines 30 29^c may be made large enough to space the seal plates apart and, in that event, the projections 29^e may be unnecessary. The center of each seal 29 is preferably provided with an aperture 29^f and these apertures are aligned with each other 35 when a plurality of seals are arranged in a vertical stack so that they may be engaged by a wire or other temporary fastening means which is extended through the aligning apertures and then bent transversely at its ends so that the 40 stack of seals is held temporarily together in a bundle or package for convenience in transporting it and placing it in the magazine of a sealing tool. A relatively soft ductile wire is perfectly employed for securing the seals together in the 45 package.

When the bundle or stack of seals has been placed in the magazine of the sealing apparatus, the wire may be pulled out of the aligning apertures 29^f to release the seals for engagement by 50 the seal feeding means which moves them successively into engagement with the sealing device of the tool in which the magazine is embodied. The projections 29^e provide point to point contacts between adjacent seals which space the 55 body portions of these seals slightly apart to facilitate the removal of the lowermost seal only from the magazine on each operation of the feeding means, in addition to reducing the frictional resistance between the lower seal and the next 60 adjacent seal during this sliding movement. Each seal employed with the sealing apparatus of the present invention is preferably formed of metal which is hard and stiff, but which has a slight resiliency and sufficient ductility to cause 65 it to retain a permanent set after the side portions 29^b have been bent around the overlapping ends of the strap.

In Fig. 3 there is shown another form of seal 30 which is in the form of a rectangular metal 70 plate having a slight transverse curvature between its longitudinal edges 30^d. This seal is provided at its ends with pairs of oppositely disposed notches or indentations 30^c, these notches being equally spaced from the lateral 75 edges of the seal at its opposite ends so that they

give the seal a tendency to bend along parallel lines extending between opposite notches when pressure is supplied to the lateral edges of the seal. When the seal is applied to the overlapping strap ends, the side portions 30^b tend to bend 5 about the lines connecting the oppositely disposed notches 30^c while the intervening portion 30^a engages one side of a strap end. As in the form of seal previously described, the seal 30 is provided with punched projections 30^e which space 10 the seals slightly apart and reduce the frictional resistance between them when they are arranged in the form of a stack. The seals 30 are provided with central apertures 30^f for engagement by a wire or other fastening member when 15 the seals are stacked upon each other to form a bundle.

When either of the seals 29 or 30 is applied to the overlapping strap ends 27^a and 27^b, as shown in Figs. 4 and 7, by the use of sealing apparatus, 20 such as that disclosed in Figs. 4 to 8, inclusive, the lateral edges of the seal are bent beneath the overlapping strap ends, as shown in Fig. 7, by the operation of the bending dies carried by the jaws of the tool, and the actuation of the 25 shearing dies serves to shear the lateral edges of the strap ends and the surrounding seal along the lines 31, as shown in Fig. 2, with a deflection of the metal between the shear lines to form downwardly projecting lugs 32. In the form of 30 joint shown in Fig. 2, there are two pairs of cuts 31 on each side of the seal and two downwardly deflected lugs which provide abutting shoulders preventing relative endwise movement of the 35 strap ends. The form of interlocking joint shown in Fig. 2 is of the type described and claimed in the United States patent of Ralph H. Norton No. 1,260,016, dated March 19, 1918, but it will be understood that after any one of the seals shown in Figs. 1 or 3 has been bent around the 40 overlapping strap ends, the strap ends and the seal may be otherwise deformed to provide an interlocking joint which prevents relative endwise movement of the strap ends.

The sealing apparatus 25, which is partially 45 illustrated in Figs. 4 to 8, inclusive, comprises a base plate 33 adapted to rest upon the surface of the box or package about which a metal strap 27 is adapted to be drawn taut and sealed. This base plate 33 may preferably carry two pairs of 50 relatively movable gripping devices (not shown) which are adapted to grip the opposite end portions of the strap, after it has been passed around a box or package, and to hold these end portions while the strap is being drawn taut. After the 55 strap 27 has been drawn taut, with the ends 27^a and 27^b thereof overlapping, these overlapping ends are secured together or sealed by the application thereto of a seal 29 (or 30), and this sealing operation is effected by a movable head 80 60 comprising a pair of side plates 81 which are pivotally mounted on a shaft 82 fixed in the lower portions of the posts 75 which are carried by the base plate 33. The plates 81 are notched on their upper sides, as shown at 81^a, to receive the shaft 65 or pin 73 when the head 80 is in its uppermost position, thus limiting the upward movement of the head. These plates 81 are adapted to receive between them a pair of jaws 83 which are pivotally mounted upon pins 84 having their ends 70 secured in these plates. Each jaw member is made up of a plurality of bending dies and a plurality of cutting dies which are arranged alternately, side by side, in each jaw member as shown particularly in Fig. 5 where the bending 75

5 dies are designated by the numeral 83^a and the cutting dies by the numeral 83^b. In this instance, there are three bending dies and two interposed cutting dies in each jaw member. The 10 die plates of the jaw members are provided on their inner edges with curved surfaces 83^c, concentric with the axes of the pivot pins 84, and these curved surfaces are adapted to move in close proximity to each other when the jaw members 15 are pivoted about their axes. Between these curved surfaces and below the line of their nearest proximity, there is mounted a seal supporting member or saddle 85 which is substantially triangular in cross-section, having 20 curved faces 85^a which are adapted to coact with the curved faces 83^c of the jaw members, as shown in Fig. 4. The saddle 85 is supported at its ends by the side plates 81 of the head and the jaws 83 are capable of relative angular movement 25 without disturbing the position of the intermediate saddle. The lower portions of the bending dies 83^a of the jaw members are provided with inwardly projecting hooks or jaws 83^d. These bending dies are undercut or recessed above the 30 hooks or jaws 83^d as shown at 83^e, and these recesses are adapted to be engaged by the edges of the seal 29 when the seal is initially placed between the jaw members with the parts in the relative positions shown in Fig. 4, but with the 35 head 80 elevated to a position wherein the notches 81^a engage the pin or shaft 73. The bending dies 83^a of the jaw 83 which is on the right hand side of the head 80, as viewed in Fig. 4, extend upwardly and outwardly from the 40 pivot pins 84 upon which they are mounted and then terminate in upwardly and inwardly inclined arms 83^f which are provided on their inner ends with curved surfaces 83^g adapted to be engaged by an operating member for effecting movement of the die plates about their pivot. At 45 the other side of the head 80, the die plates 83^a of the other jaw member 83 extend upwardly to form arms 83^h which are provided on their inner or upper sides with surfaces 83ⁱ adapted to be engaged by an actuating member.

The cutting dies 83^b which are positioned between the bending dies 83^a are mounted for relative movement with respect to the bending dies 83^a about the pivot pins 84 and they are provided on their lower ends with inclined cutting edges 83^j which, when the cutting dies of opposite jaw members are moved toward each other, are adapted to shear the lateral edges of the seal and the enclosed strap ends to form an interlocking joint of the form illustrated in Fig. 2. The cutting die plates 83^b in the jaw member 83 at the right hand side of the head 80, as viewed in Fig. 4, extend upwardly and outwardly from the pivot pin 84 upon which they are mounted and terminate in upwardly and inwardly inclined arms which are similar in form and normal position to the arms 83^f formed on the bending dies of that jaw member. At the left hand side of the head 80, as viewed in Fig. 4, the cutting dies 83^b extend upwardly from the pivot pin 84 upon which they are mounted, but are relatively short and are provided at their upper ends with inclined or curved surfaces 83^m to accommodate the adjacent operating member which is provided for the purpose of effecting pivotal movement of these die plates. The die plates 83^b in the other jaw member have inner surfaces which are also adapted to be engaged by the actuating members. For the purpose of returning the cutting die plates 83^b to their normal positions with respect

5 to the bending die plates 83^a, after these cutting die plates have been moved from their normal positions, the cutting die plates 83^b are provided with pins 83ⁿ which project laterally therefrom through elongated slots 83° which are formed in the bending die plates 83^a of each jaw member 83. These pins also project through elongated curved slots which are formed in the side plates 81 and the projecting ends of these pins are connected by springs which are adapted normally to move 10 the die plates 83^a and 83^b to their normal relative positions shown in Fig. 4.

When the die plates are in these normal positions, with the head 80 in its elevated position, the lower portions of the die plates are adapted 15 to receive between them the substantially flat seal 29, the edges 29^d of which engage the recesses 83^e formed in the bending die plates 83^a. The next operation, after the seal has been inserted, consists in lowering the head to position the seal 29 20 over the overlapping strap ends, as shown in Fig. 4. After this has been done, the bending die plates 83^a are actuated, independently of the cutting die plates 83^b, to bend the lateral portions 25 29^b of the seal downwardly and inwardly around the overlapping strap ends, as shown in Fig. 7. Following this operation, the cutting die plates 83^b are actuated to shear the lateral edges of the strap and seal to form the interlocking joint 30 shown in Figs. 2 and 8.

The bending and cutting die plates of the jaw members 83 are adapted to be actuated by a cam 90 which constitutes the hub of an operating lever 92 pivotally mounted upon a pin 93 which extends between and is secured in the side plates 35 81. When the operating lever 92 is in its normal position with respect to the side plates 81 and the jaw members 83, as shown in Fig. 4, the lower portion 90^a of cam 90 occupies a position between the arms of the bending dies, and above this 40 portion 90^a of the cam there is a curved inclined surface 90^b formed on a projection 90^d and engaged by the surfaces 83^g of the arms 83^f, while at the other side, the part 90^a has a surface 90^c which lies in contact with the surfaces 83ⁱ of the 45 arms 83^h. Assuming that a seal 29 is positioned between the jaw members, with the head 80 in its elevated position, the next step in the operation of the apparatus is to lower the head 80 by pushing downwardly upon the operating lever 92 until 50 the seal 29 is positioned over the overlapping strap ends as shown in Fig. 4. After this has been done, the operating lever 92 is moved forwardly or toward the right, as viewed in Fig. 4, thereby causing the surfaces 83^g of the arms 83^f 55 of the right hand jaw member 83 to be engaged by the surface 90^b while, at the same time, the surfaces 83ⁱ of the arms 83^h of the other jaw member are engaged by the surface 90^c of the cam, with the result that the lower portions of the 60 bending dies are moved inwardly toward each other to bend the side portions 29^b of the seal around and beneath the overlapping strap ends to form an enclosing sleeve as illustrated in Fig. 7. Upon continued movement of the operating lever 65 92, the bending dies remain substantially stationary, but the cutting dies 83^b are then actuated by other portions of the cam 90 with the result that the cutting edges 83^j of the cutting dies shear the lateral edges of the strap and seal to 70 form the cuts 31 and the projections 32 shown in Fig. 2. When these operations have been completed, the operating lever 92 is moved in the opposite direction about its pivot 93 with the result that both cutting dies and the bending dies are 75

restored to their normal positions by the actions of springs (not shown) connected to the ends of the pins 83^a.

At one side of the path of movement of the head 80 there is mounted a seal storage magazine 115 having an internal chamber of rectangular cross-section which is adapted to receive a stack of the seals 29 (or 30), as shown in Figs. 5 and 6. This magazine 115 is so positioned that the lowermost seal in the stack in the magazine is located opposite the recesses 83^c of the jaws when the head 80 is in its uppermost position. When in this position, the jaws of the head are adapted to receive between them the lowermost seal 29 which is fed thereto by means of a plunger 120 which may be manually operated independently of any other part of the apparatus or which may be actuated by the mechanism by which the strap is drawn taut around the package as disclosed in my original application above referred to. This plunger 120 is provided at its forward end with a projection 120^b which is adapted to extend over the top of the lowermost seal 29 and beneath the central portion of the next adjacent seal of the stack so that as the plunger is moved toward the left, as viewed in Fig. 5, the lowermost seal is thrust through the opening 115^c in the side wall of the magazine into a position between the jaws of the sealing tool, the seal being limited in its endwise movement by engagement with a lug 81^c formed on the outermost side plate 81 of the head. During this sliding movement of the seal the projections 29^a limit the frictional resistance of this seal on the next adjacent seal of the stack and at the same time these projections space the lowermost seal from the next adjacent seal so that there is no danger of removing more than one seal by one operation of the plunger 120.

With the forms of seals illustrated in the drawings, it will be apparent that the score lines 29^c and the notches 30^c constitute recesses or deformations which are oppositely disposed in pairs

so that they determine the lines about which the side portions of the seals bend when they are applied to the overlapping strap ends.

Although two forms of the improved seal have been shown and described by way of illustration in conjunction with the disclosure of one form of sealing apparatus which may be employed in connection with the use of seals of this type, it will be understood that the improved seal of the present invention may be embodied in various forms coming within the scope of the appended claims.

I claim:

1. A strap seal adapted to be applied to overlapping strap ends and comprising a metal plate 15 having a slight transverse curvature from edge to edge, whereby pressure applied to the edges of said seal will cause it to bend in a predetermined direction about the strap ends.

2. A strap seal adapted to be applied to overlapping strap ends and comprising a metal plate having a slight transverse curvature from edge to edge, whereby pressure applied to the edges of said seal will cause it to bend in a predetermined direction about the strap ends, said seal being 25 provided with opposite indentations at its ends adapted to cause said seal to bend along predetermined lines when applied to the strap ends.

3. A strap seal adapted to be applied to overlapping strap ends and comprising a metal plate 30 having a slight transverse curvature from edge to edge, whereby pressure applied to the edges of said seal will cause it to bend in a predetermined direction, said seal being provided with opposite indentations at its ends adapted to cause said 35 seal to bend along predetermined lines when applied to the strap ends, said seal being provided with a plurality of projections whereby said seal will be spaced slightly from adjacent seals when a plurality of said seals are arranged in a stack. 40

WILLIAM C. CHILDRESS.
